CLAIM

The ornamental design for a light emitting diode, as shown and described.

DESCRIPTION

FIG. 1 is a front side perspective view of a light emitting diode in accordance with new design;

FIG. 2 is a rear side perspective view of the light emitting diode in accordance with my new design;

FIG. 3 is a front elevational view of the light emitting diode in accordance with my new design;

FIG. 4 is a rear elevational view of the light emitting diode in accordance with my new design;

FIG. 5 is a top plan view of the light emitting diode in accordance with my new design;

FIG. 6 is a bottom plan view of the light emitting diode in accordance with my new design;

FIG. 7 is a left side end elevational view of the light emitting diode in accordance with my new design;

FIG. 8 is a right side end elevational view of the light emitting diode in accordance with my new design; and,

FIG. 9 is a front elevational view of the light emitting diode in accordance with my new design with environment shown in broken lines.

The broken line showing of environment (the remaining structure of the light emitting diode) in the Figures is for illustrative purposes only and forms no part of the claimed design.
